CLAIM

The ornamental design for a watch with a QR code, as shown and described.

DESCRIPTION

FIG. 1 is a perspective view of the watch with a QR code, showing my new design;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1; and,

FIG. 7 is a bottom plan view of FIG. 1.

The broken lines showing a wrist band in the figures depict environmental matter and form no part of the claimed design. The remaining broken lines, including a data portion of the QR code, depict portions of the watch that form no part of the claimed design.

The broken lines in the drawings illustrate environmental matter that forms no part of the claimed design.
